Patented Dec. 14, 1920.

INVENTOR:

Edward J. O'Leary
BY
Pierre Barnes
ATTORNEY

UNITED STATES PATENT OFFICE.

EDWARD J. O'LEARY, OF SEATTLE, WASHINGTON.

DIE.

1,362,573.

Specification of Letters Patent. Patented Dec. 14, 1920.

Application filed October 8, 1919. Serial No. 329,213.

To all whom it may concern:

Be it known that I, EDWARD J. O'LEARY, a citizen of the United States, residing at Seattle, in the county of King and State 5 of Washington, have invented certain new and useful Improvements in Dies, of which the following is a specification.

This invention relates to dies for use in forging machines; and has for its object the provision of a set of dies which in one operation will produce a relatively large lateral projection or lug upon an iron or steel bar by an "upsetting" operation instead of by "jumping" or welding the lug to the bar 15 as hitherto.

With this end in view the invention consists in the novel construction and combination of the dies as will be hereinafter described and claimed.

20 In the accompanying drawings, the invention is illustrated as applicable to the production of lugs from a bar which is designed to be used in the manufacture of a mast band.

25 In said drawings, Figure 1 is a view shown partly in side elevation and partly in longitudinal section of an embodiment of my invention, the male die being shown retracted and a metal bar in position to be 30 operated upon. Fig. 2 is a similar view with the male die advanced to produce the lug shown in the cavity of the female die. Fig. 3 is a horizontal sectional view with the male die in its advanced position and one 35 of the members of the female die withdrawn from the work. Fig. 4 is a perspective view showing a sample of the work produced by the dies illustrated in the preceding views.

40 In the drawings, the reference numeral 5 designates the frame of a forging machine which, as shown, is provided near one end with recesses 6 to accommodate the members of a female die to be hereinafter described.

45 Extending from such end of the machine are screw threaded rods 7 supporting an abutment bar or "stop" 8 which is held at selected distances from the machine frame 50 as by means of nuts 9.

Mounted for reciprocatory movements in the machine frame is a power operated plunger 10. The machine above referred

to may be of any well known or suitable construction.

55 According to the present invention, I provide a female die composed of two block members 11 and 11¹ having opposing faces 12, one or both of said members being 60 mounted for reciprocatory movements from and toward each other in the respective frame recesses 6.

65 Each of said die members has a longitudinally arranged groove 13 extending the entire length of the die and of a combined width equal to the width of the bar B which is to be operated upon. Said die members are provided with complementary cavities such as 14 to afford a tunnel like opening 70 extending forwardly from the rear ends 15 of the respective members to a wall face 16. The shape of said opening transversely corresponds to the transverse shape of the lugs L which are to be produced and which, 75 in the illustrated example, as shown in Fig. 4, are provided with sides L¹ slightly converging to a substantially semi-circular outer extremity L². The upper surface 13¹ of the groove 13 in proximity to the cavity 80 face 16 is desirably inclined at an angle less than a right angle with respect to said face.

85 Coöoperating with the aforesaid die is a male die having a body portion 17 provided with a shank 18 adapted to engage in a socket provided in the plunger 10.

90 Said body is provided with a longitudinal slot 19 extending the entire width of the body and forwardly from within a short distance of the shank 18. The upper bifurcation 20, hereinafter designed as the forming element, is of less length than the lower bifurcation 21 which will be hereinafter designated as the "carrier." The carrier 21 serves to support the work and bears upon 95 the floor 13² of the grooves of the die members 11 and 11¹ when the latter are brought into juxtaposition with each other. The width of the carrier element of the male die is equal to that of the cavity within the 100 other die and is of a depth to afford a space above the carrier sufficient to accommodate the bar element B of the work.

105 Said forming element 20 is of a length less than the carrier 21 and is adapted to extend into the cavity of the female die to a distance equal to the thickness of a lug

L from the cavity end 16 when the male die has been moved with the plunger to the end of its forward stroke.

The shape of the forming element part 20¹ which extends into said die cavity is of a transverse shape corresponding to that of a lug L and also said cavity. The lower surface 20² of the forming element in proximity to its forward face 20³ is arranged to be in angular relations therewith less than a right angle. 22 represents a plate removably placed within the slot 19 of the male die for regulating the position of a bar B longitudinally of the carrier.

15 The operation of the above described invention is as follows: A bar B, which is heated in the locality of a lug which is to be produced, is placed upon the carrier element 21 of the male die, extending through 20 the groove of the die member 11¹ and between the stop 8 and a filler plate 22 of suitable length to close the gap in the slot 19 when said die is in its retracted position, as shown in Fig. 1.

25 The member 11 of the female die is then brought against the complementary member 11¹ and is temporarily secured by suitable means, not shown, from separating therefrom.

30 With the parts thus arranged, the male die is then urged forward, but inasmuch as the stop 8 prevents the bar B accompanying this die, the ends of the bar will in an obvious manner be forced toward each other resulting in the hot portion of the bar being crowded into the cavity 14 of the female die by what is conventionally known as an upsetting action. The continued forward travel of the male member will thereupon 35 engage the portion of the bar which has been protruded into said cavity and is pressed between the opposing faces 20³ and 16, respectively, of the former element 20¹ and cavity to produce the lug L^b as represented in 40 Fig. 2.

45 During such lug producing operation the sloping surfaces 13¹ and 20² of the two dies coact to direct into the die cavity the material afforded for making a lug by the shortening of the bar.

50 When a lug is formed as explained above the plunger 10 is drawn back to retract the male die and the die member 11 moved away from its mate, whereupon the work can be 55 removed.

55 Where two or more lugs are to be formed from a bar, the first lug, as L^a Figs. 1 and 2, may be made without the use of the plate 22, or the latter may be used by reversing the 60 bar B in the machine for making the second lug.

Furthermore, any number of lugs may be made by substituting different lengths of plates.

65 Lugs produced by "jumping" or "upset-

ting" a hot portion of a metal bar in a die by contracting the length of the bar affords better appearing and stronger results than can be obtained by building-up, welding or cutting out methods.

What I claim, is—

1. A forging machine having a reciprocating plunger and a stop, a male die secured to said plunger for movement relative to said stop, said die being provided with means which coöperate with said stop to retain therebetween stock which is to be operated upon, a female die through which both the aforesaid die and the stock extend, said male and female dies being provided with coöperating parts for effecting the upsetting of a part of the stock within the female die.

2. In a forging machine, the combination with the machine frame, a reciprocating plunger, and a rigid stop, of a female die having a mold cavity therein and secured to the machine frame between said plunger and said stop, a male die provided with a forming element, said male die having a second element guided in said female die and serving to support work which is to be operated upon, and means provided in the male die and coöperating with the aforesaid stop for confining said work therebetween during the operative movement of the male die with 90 said plunger.

3. A lug-forming die comprising a two part separable female die provided with a mold cavity and a male die arranged for reciprocatory movements longitudinally of the female die, said male die having a work carrying portion disposed below the bottom of said cavity and a forming element arranged to be entered into and withdrawn from the cavity in the successive strokes of the male die.

4. A lug-forming die comprising a female die having a mold cavity therein, a male die provided with a lug forming element operable within said cavity, and a work supporting element provided on the male die and serving as a guide for the latter in the female die.

5. A lug forming die comprising a member consisting of two separable sections and having a mold cavity and a longitudinal slot in superposed relations, and a second member provided with two superposed spaced elements, the lower of said elements being guided in said slot and of less depth than the latter to afford a space above such element in the slot and coextensive with the space between said elements, the upper of said elements extending into said cavity and adapted to coöperate with the walls thereof to produce a lug from a heated portion of stock placed upon the lower of said elements in the operation of the die.

6. A lug-forming die comprising two separable members having in their opposing

faces complementary longitudinal grooves and cavities communicating with the respective grooves, said cavities constituting a mold corresponding in transverse shape to that of the lug which is to be produced therein, and a third member having a longitudinal slot to afford two bifurcations of unequal length, the longer of said bifurcations serving as a work carrier and operable 10 in said grooves, the shorter of said bifurca-

tions having a transverse section corresponding to that of the lug and extending into said mold.

Signed at Seattle, Washington, this 2nd day of October 1919.

EDWARD J. O'LEARY.
